US00D910932S

(12) **United States Design Patent** (10) **Patent No.:** **US D910,932 S**
Hu (45) **Date of Patent:** **** Feb. 16, 2021**

(54) **FEEDER FOR CONTROLLING ANIMAL FEEDING**

(71) Applicant: **Zhenggen Hu**, Dongta Township (CN)

(72) Inventor: **Zhenggen Hu**, Dongta Township (CN)

(**) Term: **15 Years**

(21) Appl. No.: **29/735,747**

(22) Filed: **May 22, 2020**

(51) LOC (13) Cl. **30-03**

(52) U.S. Cl. **D30/129**
 USPC ....

(58) **Field of Classification Search**

(57) **CLAIM**

The ornamental design for a feeder for controlling animal feeding, as shown and described.

DESCRIPTION

FIG. 1 is a front, right side, bottom perspective view of a feeder for controlling animal feeding showing my new design;

FIG. 2 is a rear, left side, top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
